SAFETY AUTOMATIC REGULATOR FOR TIMEPIECES

Jacob Rabinow, 1603 Drexel St., Takoma Park, Md., assignor of one-half to Max L. Libman, Vienna, Va.
Continuation of abandoned application Serial No. 785,214, June 6, 1959. This application Mar. 4, 1960, Ser. No. 13,679

5 Claims. (Cl. 58—109)

This application is a continuation of my copending patent application, Serial No. 785,214, filed January 6, 1959, for safety automatic regulator for timepieces, now abandoned.

This invention relates to the automatic regulation of timepieces wherein the setting of the hands moves the rate regulator in the appropriate direction to produce a correction in the running rate.

Automatic rate regulators are known which provide a change in the running rate of a timepiece by the ordinary operation of setting the hands to the correct time. In such regulators some expedient must be provided to prevent an excessive change in the setting of the rate regulator by the act of correcting the time indication. In my U.S. Patent No. 2,858,029, issued October 28, 1958, there is shown, among other things, a mechanism by means of which a maximum correction of the rate can be set by a single motion of the hands so that if one moves the hands, say more than five minutes, the change in rate reaches a maximum and is restrained from further motion by a suitable stop. This stop is released by the movement of the watch mechanism after some predetermined time so that another change in the rate can be made later. Other variations of a maximum stop and a subsequent release by the clockwork have also been developed by other inventors. While solving the problem of excessive correction fairly well, they suffer from the difficulty that if one were to move the hands less than the amount required for maximum correction and repeat this motion many times, a very large change in rate can be produced. This might appear, for example, in the case of a timepiece which makes a maximum correction for a five minutes setting and then latches the rate regulator at this point. If one were to move this timepiece three minutes at a time, the latch would not operate and one could make a very large error in rate, which might be done by a person ignorant of the mechanism, or by a child playing with the knob. Also, some of the mechanisms used for latching have to be made fairly elaborate and since in most cases the rate regulator is driven by friction from the hand setting mechanism, rather light and sometimes flimsy structures are employed.

It is a primary object of the invention to provide means in an automatically regulated timepiece of the type discussed above, for preventing improper operation of the rate regulating means. More specifically, it is an object of the invention to provide, in a timepiece regulator, means whereby any regulation can be made only once, regardless of the amount of regulation, and thereafter no further regulation can be accomplished until continuous operation of the timepiece mechanism releases the regulating mechanism for further operation.

A further object is to provide a simple, rugged, and inexpensive mechanism for this purpose.

The specific nature of the invention as well as other objects and advantages thereof will clearly appear from a description of a preferred embodiment as shown in the accompanying drawings, in which:

FIG. 1 is a sectional plan view, taken on line 1—1 of FIG. 2, showing the mechanism of the invention in the locked position, immediately after automatic regulation has been accomplished;

FIG. 2 is a sectional view taken on line 2—2 of FIG. 1;

2

FIG. 3 is a view similar to FIG. 1, but showing the latch released, sometime after regulation, and ready for a subsequent regulation;

5 FIG. 4 is a view similar to FIG. 3, but showing the stem retracted for a hand setting and regulating operation; and

FIG. 5 is a fragmentary schematic view of an alternative detail of my regulator.

By way of example only, the invention is shown applied to the rate regulator described in my aforesaid Patent No. 2,858,029. When the setting stem 4 is retracted for the purpose of setting the hands, as shown in FIG. 4, it carries with it member 30, which causes lever 18' to move to the left, causing disc 26, through arcuate sector 22, to engage disc 43, which is attached to the minute shaft 10. Gear 28 which is attached to disc 26 for rotation therewith, is at all times engaged with the teeth of gear sector 14, fixed to rate regulator shaft 12, which thereby changes the rate regulation as described in my aforesaid Patent No. 2,858,029. As stem 4 is rotated in the setting position, the hands are set forward or backward, depending upon the direction of rotation, through a conventional gear train (not shown) which terminates in gear 40 fixed to shaft 10 (FIG. 2). This causes a change in the rate regulation through the mechanism above described, until the arcuate sector 22 is moved sufficiently so that it disengages the two discs 43 and 26. Although I have briefly described the rate regulator shown in my aforesaid patent, it will be understood that the invention is equally applicable to any rate regulator of the type wherein the hand setting motion of the timepiece is transferred to the rate regulating mechanism through a friction drive, or an equivalent gear drive.

FIG. 1 represents the condition of the mechanism immediately after a rate regulation has been made and the stem 4 has been pushed back into its normal or running position. In this condition, a swinging lever 3, actuated by the setting stem, presses on the locking bar 5 and forces this locking bar to engage the teeth of gear sector 14, which as explained above, is fixed to the rate regulator stem 12, thus blocking the rate regulator against any further motion or adjustment. The locking bar 5 is guided at various times by the four pins 7 and 8; it is urged by a spring 9 to the left out of engagement with the regulator gear segment 14, spring 9 being so positioned as to also press the bar 5 downwardly toward stem 4. Spring 9 is anchored at one end 11 to the body of the timepiece. In the position shown, locking bar 5 is also held by latch 15, so that even if the stem 4 is again retracted, releasing the swinging lever 3 from engagement with the end of the locking bar 5, the locking bar cannot follow, despite the pressure of spring 9, because it is retained by latch 15. Thus the timepiece can again be set, but as long as the locking bar 5 is in the position shown in FIG. 1, the rate regulator cannot move, and there will merely be friction slippage between disc 43 and disc 26.

A cam actuating cam 44 is frictionally mounted on shaft 10 for rotation therewith, the frictional engagement being sufficiently light so that the cam 44 can readily slip on the shaft, although the frictional engagement is sufficient so that when cam 44 engages the hammer lever 18, it can force it back against the action of spring 20. As the shaft 10 continues to rotate in the normal operation of the timepiece, the cam 44 finally passes the end of the hammer lever 18, suddenly releasing it for rotation under the action of spring 20 with sufficient force to strike against locking bar 5 and release it from latch 15, so that under the action of spring 9 the locking bar now assumes the position shown in FIG. 3. In this position, the locking bar 5 overlies the end of swinging lever 3, and is urged lightly against the end of swing lever 3 by

a component of force exerted by spring 9. The timepiece is now ready for another setting and automatic regulating operation. When stem 4 is again pulled out into the hand setting position, the locking bar 5 is pressed down by spring 9 into the position shown in FIG. 4, where the end of the locking bar underlies the end of swinging lever 3 so that return motion of swinging lever 3 into the position shown in FIG. 1 carries the locking bar 5 with it into locking engagement as shown in FIG. 1. Another rate regulation cannot be made until the shaft 10 has completed substantially a full rotation to cause element 44 to actuate hammer lever 18 and release locking bar 5 as previously described. It will be noted that this action is independent of the amount of regulation performed and that two successive acts of regulation cannot be performed until the hammer lever 18 has been twice actuated by cam 44. It is true that the time period between possible successive operations is somewhat random, depending upon the position of cam 44 at the time the stem is moved back into the hand setting position, but the stem moves very slowly, and the chance of its being at any time precisely in the condition where it will immediately release the hammer lever 18 is so small as to be negligible in practice.

However, the risk can be still further reduced by putting a cam on the hour shaft instead of the minute shaft, whereby full rotation of the cam would then require twelve hours instead of one hour. If desired, the interval could be made even longer by the use of suitable gearing.

The hammer mechanism is shown only to illustrate one form of mechanism which is instantaneous in its action. It will be apparent that the cam 44 could act directly on locking bar 5 to release it, but this arrangement, while simple, has the possible disadvantage that it would render the locking bar 5 inoperative during the time the cam dwells against the bar, so that if a correction is made at this time the locking feature would be ineffective. However, this would not occur very often, and in any case will not interfere with the normal regulation action.

FIG. 5 illustrates another form of hammer mechanism for releasing the locking bar. In this embodiment, the shaft 10 has fixed to it a light spring 47 carrying a small hammer 41. In the course of its rotation, the hammer 41 will finally reach the dotted line position 45, where it bears against a fixed stop 42 attached to the body of the timepiece. Thereafter, as the shaft continues to rotate in a clockwise direction, the spring 40 is flexed by an increasing amount until the hammer 41 finally is carried past the point where pin 42 can any longer restrain it. Under the action of the flexed spring 40, the hammer now flies against the projection 46 on locking bar 5, to release the locking bar from latch 15 as previously described.

In the embodiment of FIG. 1, if it is desired to set the hands backwards, i.e., counter clockwise, the cam 44 can come to rest against the end of hammer lever 18; for this reason the light friction fit previously mentioned is provided, so that the element 44 merely slips on shaft 10, which has the advantage that the full rotation of the shaft 10 will be required before a subsequent rate regulation can be made. In the modification of FIG. 5, if the shaft is rotated backwards, even with the locking bar in the latched position shown in FIG. 1, the spring 47 is too light to shove the locking bar out of engagement with latch 15, and will merely flex, so that no harm is done.

It will be apparent that the embodiments shown are only exemplary and that various modifications can be made in construction and arrangement within the scope of my invention as defined in the appended claims.

I claim:

1. In a timepiece having normal running means and time-indicating means, rate regulating means, manual control means having a running position and a time-setting position, means to couple the time-indicating means to the rate regulating means when the manual control means are in the setting position, locking means actuated by op-

eration of the manual control means from the setting position to the running position to lock the rate regulating means into a fixed position after the setting of the time indicating means, and means actuated by said normal running means to release said locking means for subsequent movement of the rate regulating means.

2. In a timepiece having drive means and display means, a stem movable from a normal running position to a setting position, rate regulator means for adjusting the running rate of the timepiece, means operably interconnecting said rate regulator and said display means to change the running rate of the timepiece in accordance with a change in setting of the display means, locking means operable to lock said rate regulator means against operation, lock actuating means operable on return motion of said stem from said setting position to said running position to actuate said locking means to lock said rate regulator means against operation, and lock release means operable by said drive means to release said lock means to permit subsequent operation of said rate regulator means.

3. In a timepiece having normal running means and time-indicating means, adjustably movable rate-regulating means, manual setting means having a normal running position and a time-setting position in which the time-indicating means is set by operation of the manual setting means; friction drive means normally operative by setting operation of the manual setting means to move said rate-regulating means to change the adjustment of the rate-regulating means in a direction dependent on the direction of setting of the time-indicating means; locking means directly engageable with a movable portion of the rate regulating means to lock same in a fixed position against motion in either direction independently of motion of said manual setting means, said friction means being effective to permit setting of the time-indicating means by slipping of said drive means when said locking means are engaged; means independent of said friction drive means to move said locking means into locking position subsequently to any adjustment whatever of said rate-regulating means, and means subsequently actuated by said normal running means to release said locking means to permit a further such adjustment of said rate-regulating means.

4. In a timepiece having normal running means and time-indicating means, adjustably movable rate-regulating means, manual setting means having a normal running position and a time-setting position in which the time-indicating means is set by operation of the manual setting means; friction drive means normally operative by setting operation of the manual setting means to move said rate-regulating means to change the adjustment of the rate-regulating means in a direction dependent on the direction of setting of the time-indicating means; locking means directly engageable with a movable portion of the rate regulating means to lock same in a fixed position against motion in either direction while permitting setting movement of said time-indicating means by slipping of the friction drive means, locking operating means effective after completion of a change of adjustment of the rate-regulating means to operate said locking means to lock said rate-regulating means against further subsequent movement, and means subsequently actuated by said normal running means to release said locking means to permit a further adjustment of the rate-regulating means.

5. In a timepiece having normal running means and time-indicating means, adjustably movable rate-regulating means, manual setting means having a normal running position and a time-setting position in which the time-indicating means is set by operation of the manual setting means; friction drive means normally operative by setting operation of the manual setting means to move said rate-regulating means to change the adjustment of the rate-regulating means in a direction dependent on the direction of setting of the time-indicating means, locking means directly engageable with a movable portion of the rate

regulating means to lock same in a fixed position against motion in either direction independently of motion of said manual setting means, said friction means being effective to permit setting of the time-indicating means by slipping of said drive means when said locking means are engaged; means to move said locking means into locking engagement with said movable portion after each change of adjustment of the rate-regulating means, and

means subsequently actuated by said normal running means to release said locking means to permit a further such adjustment of said rate-regulating means.
